UNITED STATES PATENT OFFICE.

CHARLES F. PYM, OF DETROIT, MICHIGAN, ASSIGNOR, BY MESNE ASSIGNMENTS, TO UNITED SHOE MACHINERY CORPORATION, OF PATERSON, NEW JERSEY, A CORPORATION OF NEW JERSEY.

LASTING-BINDER.

1,306,121.

Specification of Letters Patent.

Patented June 10, 1919.

Application filed May 9, 1913, Serial No. 766,472.

Renewed September 5, 1916. Serial No. 118,548.

To all whom it may concern:

Be it known that I, CHARLES F. PYM, a subject of the King of England, residing at Detroit, in the county of Wayne and State 5 of Michigan, have invented certain new and useful Improvements in Lasting-Binders, of which the following is a specification, reference being had therein to the accompanying drawings.

- 10 In lasting boots and shoes it has been found, under some conditions, to be desirable to perform the operation of shaping or forming the upper around and against the end portion of the last independently of the operations of forming the edge portion 15 of the upper down upon the inner sole and securing it, as explained in my companion application Ser. No. 766,471, for improvements in processes of lasting boots or shoes.
- 20 One object of this invention is to provide improved means for binding an upper evenly and smoothly upon an end portion of a last after it has been worked into that position and, it may be, for holding the 25 upper until it is secured to an innersole upon the last bottom. For use in practising the method described in said application it is desirable that the binder be so formed and that it be detachably secured in place in such 30 a way that neither the binder nor the securing means shall interfere with the working over, forming down, and securing of the edge portion of the upper at said end portion of the shoe, thus permitting said operations of lasting over and securing the edge 35 portion to be performed at any time subsequent to the application of the binder and in any desired manner. A further object of the invention is to provide a simple, cheap and 40 conveniently applicable binder, capable of repeated use in any method of lasting, for holding a lasted end portion of an upper firmly in place upon the last against distortion or displacement until or during the 45 securing of the edge portion of the upper to the innersole of the shoe.

A feature of the invention consists in a binder member such, for example, as a flexible strip or band provided with one or more 50 projections for use in retaining the binder in its proper relation to the shoe. In the construction shown the binder strip is provided at its ends with flanges adapted to lie upon the bottom of the shoe, the strip and flanges being shaped relatively for the strip

to embrace the side face of an inverted lasted shoe below the plane of the shoe bottom and for the flanges to extend inwardly over the shoe bottom, said flanges being formed to enable them to be detachably secured to the 60 shoe bottom, as for example, by having holes through which tacks may be driven.

The foregoing and other objects and features of the invention, including certain more important details of construction, will 65 appear in connection with the following description of the illustrative embodiment of the invention and will then be pointed out in the claims.

In the drawings:—

Figure 1 is a perspective view of a partially lasted shoe showing a binder embodying the invention applied thereto.

Figs. 2, 3 and 4 are perspective views of other forms of binders detached;

Fig. 5 is a plan view of a binder of modified form; and

Fig. 6 is a sectional view of a further modified binder illustrating its application and a means for drawing it to place.

The binder illustrated as embodying this invention comprises a ribbon or strip 16, Fig. 1, of flexible sheet material, of which sheet brass is a satisfactory example, of suitable length to extend around the end of the 85 toe of a shoe and back along each side of the forepart such distance as it is usual or desirable to bind the upper in the lasting operation. This binder, in the form constituting the illustrated embodiment of this invention, is adapted to be applied around the toe of the last to clamp and hold the upper of either a welt or a McKay shoe to the side face of the last, although this invention is not limited to such use. In addition to the 90 body or band portion the illustrated binder comprises an attaching portion at each end consisting of a lateral flange 17 bent from one edge of the body portion. As shown in the drawings, where the above described 95 special use of the invention as an outer binder is illustrated, the attaching flanges are integral lateral extensions of the strip and are bent inwardly to lie over the marginal portion of the shoe bottom and be fastened down upon the upper material and into the outer face of the sole. For greatest utility it is proposed to manufacture the binder of material which will permit of repeated use on different shoes, and the flanges 100

110

are formed to enable them to be detachably secured to the shoe bottom. Such material available for the purpose cannot be successfully perforated by the fastenings, such as 5 lasting tacks, usually employed for securing binders in place and the flanges are therefore provided with openings, Fig. 1, through which holding tacks 18 can be driven into the shoe bottom stock. It will be understood, however, that the invention in its 10 broader aspects is not limited to this particular means of attachment.

The binder may be clamped around the toe by outside pressure, as by an end 15 bracing means in an end lasting machine or means operating as described in my prior Patent 1,126,271, or by application of tension to one or both ends of the binder, and for the latter purpose the flanges are provided with eyes 19 adapted to be engaged 20 by a tool such as 31 in Fig. 6, or such as the binder tightening device shown in Letters Patent 1,084,311.

It will be noted that for the use illustrated in Fig. 1 in which the band is bent around the outside of the toe the flanges are formed on the upper edges of the strip and are bent inwardly therefrom. The same band 16 is adapted to be used for 30 binding the upper to the innersole lip of a welt innersole by bending the band reversely and turning it over so that the flanges extend from the edge which is lowermost and lie upon the upper that has been 35 lasted over the marginal portion of the shoe bottom.

In the illustrated use of the invention the flanges 17 serve to locate the adjacent portions of the band or strip 16 in proximate relation to the edge of the inverted shoe. It is within this invention to extend this function, as for example, by the construction shown in Figs. 4 and 6 where the flange is extended throughout the length 45 of the band, being reduced in width around the toe as at 30 and also joined to the body portion by a curve instead of an angle in these figures, whereby to tend to clamp the upper to the edge of the top face of the innersole of the inverted shoe, and being notched in Fig. 4. The notches in Fig. 4 present spaces on the margin of the shoe bottom in which lasting tacks can be driven as in Fig. 1, and the notches are arranged 50 to present inturned sharp prongs 28 between them which are adapted to engage the margin of the upper in a way to assist in holding it from slipping under the band. In the constructions shown in Figs. 2 and 55 60 65 the function of preventing the body portion of the band from slipping down around the toe and also the function of clamping the upper to the edge of the innersole, are performed by individual inwardly curved flanges or lugs 21 and 26.

In binding the upper against the outer face of a last having a thin or receding toe, as indicated in dotted lines in Figs. 2 and 6, it is sometimes advantageous to guard against the binder slipping up as well as 70 or instead of slipping down. For this purpose the binder may be provided with suitably located depending flanges or lugs such as indicated in Fig. 2 at 22 and at 24 in Fig. 3. 75

While the invention is described herein by reference to a convenient practical embodiment illustrated in the drawings, it will be understood that the invention in its broader aspects is not limited to the 80 precise details of construction shown.

Having explained the nature of this invention and described a preferred embodiment thereof and how the invention may be used, I claim as new and desire to secure by Letters Patent of the United States:

1. A binder for use in lasting boots or shoes comprising a metal strip and a laterally bent flange on each end of the strip adapted to lie upon the marginal portion 90 of the bottom of the shoe and provided with an opening to receive means for detachably securing said ends to the shoe.

2. A binder for use in lasting boots or shoes comprising a metal strip to engage the outer surface of the upper at the end portion of the shoe, and laterally projecting portions extending from each edge of said strip, certain of said projections extending over the bottom face of the shoe and being formed for holding engagement with tacks for detachably securing the strip to the shoe. 95

3. A binder for use in lasting boots or shoes comprising a flexible strip adapted 105 to engage the outer surface of an upper upon the end portion of a last adjacent to the edge of the sole portion and hold the upper against said end portion, said strip having a lug at the extreme end of the last 110 to engage the upper side of the toe portion of the upper and being formed at its ends for detachably securing the same to the shoe. 115

4. A binder for use in the process of lasting boots or shoes comprising a flexible strip adapted to engage the outer surface of an upper upon a last below the plane of the bottom surface of a sole upon the last, and laterally extending portions on the edges of said strip to engage respectively the bottom face of the lasted shoe and the outer surface of the upper at a distance from the edge of the sole. 120

5. A binder for use in lasting boots and shoes comprising a ribbon or strip having a laterally bent flange at each end adapted to project over the bottom of the shoe, said strip and flanges being shaped relatively for the strip to embrace the side face of an in- 125 130 135

- verted lasted shoe below the plane of the shoe bottom and for the flanges to extend inwardly over the shoe bottom, and said flanges being formed to enable them to be 5 detachably secured to the shoe bottom.
6. A binder for use in lasting boots and shoes comprising a ribbon or strip of bendable material adapted to embrace the side faces of a toe below the shoe bottom and 10 provided at both end portions with inturned projections having previously formed means for use in securing the strip in binding relation to the toe of the shoe.
7. A binder for securing an upper in 15 lasted position around the toe of a last, comprising a band of flexible material having integral attaching flanges at its ends bent from one edge at substantially right angles to the body portion of the band to lie flat 20 upon the margin of the shoe bottom and adapted to be attached to the shoe bottom stock.
8. A binder for securing an upper in 25 lasted position around the toe of a last, comprising a band of flexible material having integral attaching flanges at its ends bent from one edge at substantially right angles to the body portion of the band, said band being adapted to be applied to a shoe with 30 its width extending perpendicular to the plane of the shoe bottom and said flanges lying parallel with said plane and formed for detachably securing the band under toe binding tension to the shoe bottom stock.
- 35 9. A binder for securing an upper in lasted position around the toe of a last, comprising a band of flexible material adapted to be applied to the outer face of the toe of a shoe and having a portion on its upper 40 edge where it extends above the shoe bottom bent inwardly to lie upon the margin of the shoe bottom and prevent it from slipping down and a depending lug bent inwardly from its lower edge to prevent the band 45 from upward displacement.
10. A binder for securing an upper in 50 lasted position around the toe of a last, comprising a band of flexible material having an inwardly inclined upper edge portion adapted for engagement with the marginal portion of the upper above the edge of the shoe bottom, and means by which to fasten the band in toe binding relation to a shoe.
- 55 11. A binder for securing an upper in lasted position around the toe of a last, com-
- prising a band of flexible metal having an inturned flange portion connected to the body of the band by a curved face adapted to clamp the upper to the edge of the bottom face of the innersole when the band is applied in binding relation to the toe, and means for use in securing the band in toe binding position. 60
12. A binder for use in retaining an upper in conformity to the contour of the end portion of a last comprising a flexible member adapted to extend around the end portion of the upper, said member having a flange extending in transverse relation to its lengthwise dimension and adapted to be secured in overlapping relation to a portion of the upper on the bottom of the last to fasten the binder in place. 65
13. A binder for use in retaining an upper in conformity to the contour of the end portion of a last comprising a flexible member adapted to extend around the end of the shoe exteriorly of the periphery of the shoe bottom and having at its ends projections extending in transverse relation to the lengthwise dimension of the binder and adapted for attachment to portions of the shoe materials that overlie the bottom of the last to fasten the binder in place. 70
14. A binder for use in retaining an upper in conformity to the contour of the end portion of a last comprising a flexible band adapted to extend around the end of the shoe exteriorly of the shoe bottom and having at its ends projecting flanges adapted to be secured in overlapping relation to the shoe materials on the bottom of the last to fasten the binder in place. 80
15. A binder for use in retaining an upper in conformity to the contour of the end portion of a last comprising a flexible member adapted to extend around the end of the upper, said member having a projection adapted for attachment to the shoe materials on the bottom of the last and another projection constructed for engagement with the outer surface of the upper to prevent the binder from slipping laterally. 90
- In testimony whereof I affix my signature in presence of two witnesses.
